[57] CLAIM

The ornamental design for a table lamp, as shown and
described.

DESCRIPTION

FIG. 1 is a perspective view of a table lamp showing my
new design;

FIG. 2 is a side view thereof on an enlarged scale;

FIG. 3 is a rear view thereof on an enlarged scale;

FIG. 4 is a top view thereof on an enlarged scale;

FIG. 5 is a perspective view thereof with the removable

head in the inverted position;

FIG. 6 is a perspective view of the removable head on
an enlarged scale, the remainder of the lamp being omitted
for convenience of illustration.
